UNITED STATES PATENT OFFICE

2,482,360

STRAIGHTEDGE DEVICE FOR DETERMINING ANGLES BETWEEN CYLINDERS AND THE LIKE

Wilson K. Moore, San Diego, Calif., assignor of forty-nine per cent to Charles B. Leedy, National City, Calif.

Application July 14, 1944, Serial No. 544,850

2 Claims. (C. 33—75)

1

This invention relates to a novel and improved device for finding varying angles and marking ninety degree centers on vertical and horizontal lines of hollow and solid cylinders such as, for example, pipes, rods and the like.

In carrying out the principles of the invention, I have evolved and produced a simple and reliable device expressly designed to locate outside or inside vertical and horizontal centers of pipes and solid cylinders in any size, this for conveniently laying out ordnance, preparatory to cutting various degree angles, or quartering the diameter of a pipe or cylinder.

Briefly, the preferred embodiment of the invention is characterized by a pair of substantially V-shaped saddles, these constituting the base members and being hingedly connected together, there being gauge means at the hinged joint of the adjacent ends of said saddles, and one of said saddles being provided with an especially constructed punch unit, the latter for indenting and marking the desired points about the circumference of the work, whereby to effectively achieve the desired aims.

More particularly, novelty is predicated upon a device of the class stated wherein the spring-pressed punch is adapted to be struck with a hammer or the like, the cylinder carrying the punch thereof being provided with a suitably calibrated turnable dial and said dial serving as a mount for diametrically opposite parallel spirit levels, these being shiftable to points of vantage in accurately determining the circumferentially shifted positions of the device, as a whole, prior to indenting and marking the work.

Other features and advantages will become more readily apparent from the following description and the accompanying illustrative drawings.

In the drawings, wherein like numerals are employed to designate like parts throughout the same—

Figure 1 is a side elevational view of an angle and center finder and marker designed and constructed in accordance with the principles of the instant invention.

Figure 2 is a top plan view of the same.

Figure 3 is a section, on an enlarged scale, taken on the plane of the line 3—3 of Figure 2, looking in the direction of the arrows.

Figure 4 is a central vertical sectional and elevational view, this on the line 4—4 of Figure 3, looking in the direction of the arrows.

Figure 5 is a section on the plane of the line 5—5 of Figure 2.

2

Referring now to the drawings by distinguishing reference numerals, it will be observed that the base is made up of complementary adapters 6 and 7, these of corresponding or variable lengths, as desired, substantially V-shaped in cross-sectional form to saddle upon the work 8 as shown diagrammatically in Figure 3. If desired, either one or both adapters may be provided with appropriately calibrated scales, one being indicated at 9 in Figure 1. The adapters are also provided with suitably arranged and shaped apertures 10 serving as sights and permitting inspection during the operative use of the invention. The adjacent or abutting ends of the adapters are provided with coacting pairs of ears 11 and 12, these pierced by a hinge bolt 13 (see Figure 5), the threaded end 14 of the bolt being provided with a thumb-nut 15 for clamping purposes. At this point of hinging connection, said adapters are provided with coacting indicators. These indicators are segmental in general configuration and are in opposed alignment, the one on the adapter 6 being denoted at 16 and the companion indicator, on the adapter 7 being differentiated by the numeral 17. The latter indicator telescopes into the first-named indicator 16 and is provided with a suitably graduated measuring scale 18, as shown in Figure 2. These coacting indicators serve to provide for accurate determination of the angularity of the adapters 6 and 7 when they are used in conjunction with work parts at different angles in relation to one another (see the dotted line adjustment in Figure 1).

As previously mentioned, the adapter 6 is provided with a right angularly disposed punch unit 19. This comprises (see Figure 4) a cylinder 20 appropriately anchored in the crest or crown of the adapter. It is provided in its upper end with a closing plug 21 centrally bored to accommodate the impact extension 22 on the upper end of the punch 23. The body portion of the latter fits snugly in the cylinder and the upper shouldered end is provided with a coiled return spring 24, this surrounding the impact element 22 resting on the body at one end and against the plug-cap at the opposite end. The lower reduced extension 25 is properly pointed, this to provide an indentation in the work 8.

The punch unit also includes a disk 26 provided with marginal scales 27, these coacting with pointers 29 and 30 at diametrically opposite points, the pointers being on the cylinder 20. The disk is mounted for rotation on a screw-threaded stud 31 equipped with a binding nut 32 for convenient rotation and adjustment pur-

poses. As previously stated this disk is a carrier or mount for diametrically opposite spirit levels 33 and 34, respectively. The levels are arranged in predetermined relation with respect to the graduations of the two selectively usable scales 27.

This centering device speedily and accurately finds vertical and horizontal centers at 90 degrees apart without an aid of any tool, protractor or instrument. When finding the upper vertical center of a pipe, the adapter is simply placed or saddled on the outside contour or circumference of the pipe as shown in Figure 3. The level 34 indicates, by its bubbles, when dead-center, that is, top dead-center has been found or located. Then by taking a hammer or the like and striking the punch, this provides an indentation to guide the user in taking the next successive steps. To find a horizontal center ninety degrees from the top dead-center, the user simply places the saddle adapter on the pipe in a horizontal position. The disk 26 can be adjusted to bring the desired level conveniently into play, whereupon the punch is again struck to form the second indenture, this in the manner before explained.

This device is usable by pipe fitters, welders, and oil field pipe layout crews. It can be used for inside as well as outside operations in larger pipes. The extension adapter 7 is useful in conjunction with the adapter 6 and punch unit 19 in achieving desired results when the pipes or work parts are at different angles from each other, ranging from right angles to intermediate angles between these two extremes.

Much of the description stresses the combination of the punch device 19 with the adapters 6 and 7. It is to be noted, however, that the adapters 6 and 7 may be used in conjunction with each other somewhat independent of the punch unit or device 19. To this end, please observe in Figure 1 that the adjacent hinged ends of the parts 6 and 7 are cut away on the undersides so that it is possible to use these devices, that is, the parts 6 and 7, to be swung up at right angles to each other either upwardly as shown in dotted lines, or downwardly (not shown), or swung into the same plane with one another as shown in full lines. Of course, any intermediate position between the parts is also within the range of utility of the structure. These devices 6 and 7, in conjunction with the indicating elements 16 and 17, constitute the angle finding phase for cylinders and the like.

It is to be noticed also that the lower end of the cylinder is closed as shown, for instance, in Figure 4 and that the lower end portion of the punch is reduced and the shouldered portion engages the closed lower end of the cylinder. It is possible by using the set-screw 35 to withdraw the punch completely into the body of the cylinder against the tension of the spring and to lock

it in this inwardly retracted position by said set-screw. This closes the pointed end 25 in an out-of-the-way position.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed is:

1. In an angle finder for cylinders and the like, a pair of elongated complementary work-contacting adapters substantially V-shaped in cross-section from end to end and hingedly connected to one another at their inner ends and provided at said inner ends with coacting measuring and indicating elements, said hinged ends being obliquely cut away in angular directions to permit said adapters to be disposed in a plane with one another, or at different angular positions for angle finding purposes.

2. In an angle finder for cylinders and the like, a pair of elongated complementary work-contacting adapter members, substantially V-shaped in cross-sectional form from one end to the other, the inner vertex portion of the respective members being hingedly connected together and the adjacent inner ends of said members being beveled downwardly and outwardly from the hinge connection, when said members are in longitudinal alignment, and said beveled ends permitting the members to be arranged with respect to each other in different angular positions for many varying angle-finding purposes, one adapter member being provided with a hollow segmental part, this on the vertex portion of said member, the remaining member being provided with a similar segmental part and said parts fitting telescopically together and having coacting calibrations for measuring and indicating purposes.
